UNITED STATES PATENT OFFICE.

FRANK SHUMAN, OF PHILADELPHIA, PENNSYLVANIA, ASSIGNOR TO THE
CONTINUOUS GLASS PRESS COMPANY, A CORPORATION OF PENNSYLVANIA.

DESIGN FOR SHEET-GLASS.

No. 37,803.

Specification for Design.

Patented Jan. 30, 1906.

Application filed December 18, 1905. Serial No. 292,383. Term of patent 14 years.

To all whom it may concern:

Be it known that I, FRANK SHUMAN, of the city and county of Philadelphia, State of Pennsylvania, have invented a new, original, and ornamental Design for Sheet-Glass, of which the following is a specification, reference being had to the accompanying drawing, forming part thereof, and which shows a plan view embodying my design.

I claim—
The ornamental design for sheet-glass as shown.

FRANK SHUMAN.
